UNITED STATES PATENT OFFICE.

DAVID CHAMBERS, OF PORTLAND, OREGON.

HYDROCARBON-BURNER.

1,112,891.

Specification of Letters Patent.

Patented Oct. 6, 1914.

Application filed June 30, 1914. Serial No. 848,228

To all whom it may concern:

Be it known that I, DAVID CHAMBERS, a citizen of the United States, residing at Portland, in the county of Multnomah and 5 State of Oregon, have invented a new and useful Improvement in Hydrocarbon-Burners, of which the following is a specification, reference being had to the accompanying drawings.

10 My invention relates to a class of devices used for generating and burning gases in furnaces and stoves for fuel purposes.

The object of my invention is to provide an apparatus similar to that described in 15 Letters Patent No. 1,047,388, heretofore issued to me on December 17, 1912, for an improvement in hydrocarbon-burners, and particularly for improvements upon the device described in my said patent. I now propose 20 to change the form of the retort by substituting a pipe and also to change the form of the mixing chamber. I attain these objects as well as other advantages, by the construction, combination and arrangement of parts 25 illustrated in the accompanying drawings which form a part hereof.

Figure 1 is a sectional elevation of the device longitudinally thereof shown as arranged in a stove. Fig. 2 is a plan view of 30 the device. Fig. 3 is a sectional view on the lines 3-3 of Fig. 1. Fig. 4 is a sectional view on the lines 4-4 of Fig. 1.

Like numerals or letters refer to like parts throughout the views.

35 A is a pipe retort of rectangular form. It has a vertical part which is connected with a pipe 5 leading from a source of oil, gasoline or distillate supply. It is removable from the pipe 5 by the union nut 6. The 40 pipe A extends upward for a suitable height from its connection with the fuel pipe 5. From this point it extends horizontally in courses until it forms a rectangular shape. The outer end is closed and in its lower side 45 near the end is a discharge opening 7.

B is a frame into which the pipe A extends and it is provided with supports 8-8' upon which the horizontal parts of the pipe A rest.

50 C is a cylindrical mixing chamber, threaded on its upper end and having an opening 9 near the same, of a diameter to allow the end of the pipe A to pass through. Within the lower part of the chamber C a vertical 55 gas conveying tube 10, open at both ends, is rigidly secured. The retort opening 7 is

over the center of tube 10, and the lower end of the latter does not extend quite flush with the lower end of the chamber C. There is also space about it in the chamber. 60

D is an air supply pipe which has its vertical part inserted into a socket and is supported therein by the frame B at one side of the support 8'. A small section 13 of threaded pipe is placed in the frame to engage the supply pipe D and hold it in the desired position. This section is intended to connect with means furnishing an air supply from without the furnace or stove. This pipe is curved and extends downward within the 70 central part of the frame B. Its upper end is turned downwardly and threaded within and the upper end of the chamber C is there-in rigidly secured at a height to allow the 75 passage of the retort pipe A into the chamber C and so that the pipe A may rest evenly upon the supports 8-8'. A small fire bed 11 is rigidly secured upon the frame B below the chamber C. A cock 12 is placed in the supply pipe 5. 80

It will now be seen that when this device is set up within the fire box of a furnace or stove of the ordinary type, a small quantity of liquid inflammable material is placed on the fire bed 11 and ignited. This burns until the pipe A has been heated sufficiently. The cock 12 is then opened and a flow of distillate or gas producing fluid allowed to flow under pressure into the heated pipe. The liquid instantly forms a gas which is forced 90 downward through the tube 10 where it mixes with air supplied through the pipe D alongside the tube in the chamber C. This is ignited from below and the flames thereof spread downward and outward as indicated 95 by the arrows. Thereafter the same flames keep the pipe heated so that it provides a continuous flow of gas as it mixes with the air supply, and of a consistency to make a suitable combustible fluid. The flame thus 100 created is circular and by regulating the supply, by means of the cock 12, the desired intensity of heat can be maintained.

It will be further seen that the device may be assembled by first installing the frame 105 rigidly within a furnace or stove, with the pipe 5 attached and extending to a source of fuel supply. The chamber C is attached to the pipe D as shown. The retort A is secured in position by the union nut 6. The pipe D is then set into its socket and swung 110 around so as to receive the end of the retort

A in the opening 9. It is also practicable to assemble the retort A, the chamber C and pipe D in position as illustrated in Fig. 1 and then drop the whole into operating position and secure the device there by means of the nut 6.

It is likewise apparent that the retort being a pipe and easily removable from the remainder of the apparatus, a new retort can 10 be quickly and cheaply substituted. This is a decided advantage over my previous device because a chief trouble with gas burners is that they carbonize within, and cleaning or substitution is too expensive to make them 15 economical or satisfactory in operation.

Having thus described my invention, I claim:

1. A hydro-carbon burner comprising a rectangular pipe retort horizontally disposed, having one end connected with a source of fuel supply, its free end closed and a vertical discharge opening in the lower side of the retort near said closed end, an air pipe having its lower end connected with a source of air supply, its upper end opening downward over the free end of the retort, and a vertical cylindrical mixing chamber having its upper end rigidly secured in the upper end of the air pipe, also having an opening near the upper end in its side and receiving the free end of the retort through the same, also being provided with a verti-

cal tube of less diameter rigidly secured within the lower part of the chamber with space around it and being alined with the retort discharge opening above it, substantially as described. 35

2. A hydro-carbon burner comprising a pipe retort of rectangular form horizontally disposed, having one end connected with a source of fuel supply, its free end closed and a vertical discharge opening in the lower side of the retort near said closed end, an air pipe having its lower end connected with a source of air supply, its upper end opening downward over the free end of the retort, a vertical cylindrical mixing chamber having its upper end rigidly secured in the upper end of the air pipe, also having an opening near the upper end in its side and receiving the free end of the retort through the same, also being provided with a vertical tube of less diameter rigidly secured within the lower part of the chamber with space around it and being alined with the retort discharge opening above it, substantially as described. 40 45 50 55
